ROTARY TOOL-HEAD FOR LATHES.

SPECIFICATION forming part of Letters Patent No. 690,290, dated December 31, 1901.

Application filed August 6, 1901. Serial No. 71,016. (No model.)

To all whom it may concern:

Be it known that we, ERNST HUHN and ALBRECHT WAGNER, citizens of the Empire of Germany, residing at Leipsic, Germany, have **5** invented certain new and useful Improvements in Rotary Tool-Heads for Lathes, of which the following is a specification.

This invention relates to an improved rotary tool-head for lathes which is arranged **10** at an angle of inclination to the axis of the lathe-spindle and adapted to be shifted by suitable mechanism during the return motion of the tool-head, so that the next tool is placed in position for work; and the invention **15** consists of a rotary tool-head comprising a carriage for supporting the tool-head at an angle of inclination to the axis of the lathe-spindle, means for intermittently rotating the tool-head during the return of the carriage, **20** means for locking the tool-head, and means for releasing the locking mechanism during the return motion of the carriage.

In the accompanying drawings, Figure 1 represents a vertical longitudinal section of **25** our improved rotary tool-head for lathes; and Fig. 2 is a plan view of the same, partly in horizontal section on line 22, Fig. 1.

Similar letters of reference indicate corresponding parts.

The support for our improved rotary tool-head consists of a carriage *a*, which is reciprocated on the rails of the bed-frame *b* in the usual manner. The carriage *a* is provided **30** with an inclined seat, to which is attached an intermediate piece *c*, which furnishes a guideway for the rotary tool-head *d*, that is arranged, like the seat of the carriage, at an angle of inclination to the axis of the lathe-spindle. A number of tool-sockets *e* are **35** drilled into the head *d* in such manner that the axis of all the sockets *e* intersect each other at a point *z*, located in the continuation of the axis of the lathe-spindle, as shown in dotted lines in Fig. 1. By means of the index-holes *f*, of which a number corresponding **40** to the socket-holes *e* are arranged in the tool-head, and the index-bolt *g* the tool-head *d* is locked in such a manner that the axis of one tool-socket *e* is always in line with the **45** axis of the lathe-spindle *h*. The axis of the **50**

tool-socket *e*, which is located opposite to the lathe-spindle *h*, coincides with the axis of the spindle, the center of the intermediate guideway *c*, and the center of an opening *r*, which is arranged in the carriage *a*, so that **55** work-pieces of greater length can be passed freely through the tool-head *d* and carriage *a*.

For turning the tool-head two bevel-wheels *i* and *k* are arranged, one being attached to the under side of the tool-head, the other to **60** a shaft *l*, turning in bearings of the carriage. The position of the bevel-wheels *i* and *k* corresponds to the position of the tool-head toward the carriage *a*. To the shaft *l* of the bevel-wheel *i* is keyed a shifting disk *m*, **65** which during the return motion of the carriage *a* is turned by engagement with the shifting lug *n* on the bed-frame *b*. During the return motion of the carriage *a* a lever *o*, which serves to actuate the index-bolt *g*, **70** is simultaneously oscillated, so as to withdraw the index-bolt. The lever *o* is arranged in the carriage in such relation to the index-bolt *g* that the lower end is raised out of the line of gravity, so that the weight **75** thereof exerts a constant upward force upon the index-bolt and keeps the upper end of the same in engagement with the index-opening *f* until the lower end of the lever is raised by passing over the lug *n* in the backward motion of the carriage, thereby withdrawing the index-bolt and permitting the rotating of the **80** tool-head.

The operation of our improved tool-head is as follows: When the tool-head *d* is located **85** in its working position, as shown in the drawings, the index-bolt *g* is locked into one of the index-openings *f* and holds thereby the tool-head *d* firmly in position. When the carriage *a* is moved backward, the lower end of **90** the index-lever *o* is made to slide over the inclined end of the lug *n*, so as to pull the index-bolt *g* in downward direction and release the tool-head. At the moment when the index-bolt *g* is withdrawn from its index-opening **95** *f* the pin *p* of the shifting disk *m* abuts against the shifting lug *n*, arranged on the bed-frame *b*, so that motion is transmitted by the bevel-wheels *i* and *k* to the tool-head, so as to turn the same on its support. The turn- **100**

ing of the shifting disk *m* brings the next pin *p'* along the face *q* of the shifting lug *n*, so that it takes, after the shifting motion is completed, the position before occupied by 5 the pin *p*. The tool-head *d* is then locked again by the index-bolt *g* for the action of the next tool, and so on.

Having thus described our invention, we 10 claim as new and desire to secure by Letters Patent—

1. In a lathe, the combination with a reciprocating carriage and a rotary tool-head supported thereon at an angle of inclination to the axis of the lathe-spindle, of means for locking the tool-head consisting of a locking-bolt arranged in said carriage, index-openings provided in the bottom of said tool-head, a lever connected with said locking-bolt and having the lower end raised out of the line 15 of gravity, means for actuating said lever and said locking-bolt upon the return of the carriage, and said latter means adapted to intermittently rotate said tool-head, substantially as set forth.

2. In a lathe, the combination with a reciprocating carriage and a rotary tool-head supported thereon at an angle of inclination to the axis of the lathe-spindle and having a plurality of tool-sockets, of means for intermittently rotating said head, consisting of a bevel-gear on the bottom thereof, a bevel-wheel, a shaft, a shifting disk provided thereon, a plurality of pins projecting therefrom corresponding to the number of said tool-sockets, means for releasing the same, said latter means adapted to operate said rotating means and said locking means upon the return of the carriage, substantially as set forth.

In testimony that we claim the foregoing as 40 our invention we have signed our names in presence of two subscribing witnesses.

ERNST HUHN.
ALBRECHT WAGNER.
